UNITED STATES PATENT OFFICE.

ALVIN DEVINE, OF RANTOUL, ILLINOIS.

CHECK-ROWER FOR CORN-PLANTERS.

SPECIFICATION forming part of Letters Patent No. 367,964, dated August 9, 1887.

Application filed May 26, 1887. Serial No. 239,485. (No model.)

To all whom it may concern:

Be it known that I, ALVIN DEVINE, of Rantoul, in the county of Champaign and State of Illinois, have invented a new and Improved 5 Check-Rower for Corn-Planters, of which the following is a full, clear, and exact description.

My invention relates to an improvement in check-rowers for corn-planters, and has for its 10 object to provide a planter that is operated from a wire or rope stretched at the side, wherein the wire need not be detached at the ends when the planter is reversed, and also wherein the operating mechanism will be 15 strong and simple and not liable to lose motion by slight wear.

The invention consists in the construction and combination of the several parts, as will be hereinafter fully set forth, and pointed out 20 in the claims.

Reference is to be had to the accompanying drawings, forming a part of this specification, in which similar figures of reference indicate corresponding parts in all the views.

25 Figure 1 is a plan view of the planter. Fig. 2 is an end view thereof. Fig. 3 is a side view of the planter. Fig. 4 is a transverse vertical section through the machine. Fig. 5 is a detail plan view of the drop-arm, and Fig. 6 is a 30 section on line $\alpha\alpha$ of Fig. 4.

In carrying out the invention the frame 1 is provided with the ordinary runners, 2, seed-boxes 3, and the ordinary sliding drop-bar, 4, whereby the flow of seed is regulated from the 35 boxes.

To the inner forward ends of the seed-boxes, near the top, outwardly-extending angle-irons 5 are secured, adapted to support a transverse bar, 6, centrally which bar, upon the rear edge, 40 a downwardly-projecting tubular bracket, 7, is secured. To the upper side of the bracket 7 a flanged tube, 8, is vertically attached, the aperture in said tube aligning the aperture in the bracket.

45 A rod, 9, provided with an elongated slotted head, 10, is loosely entered the apertures of the flanged tube 8 and bracket 7, the head of said rod having a bearing upon the flange of the tube 8.

50 The lower end of the rod 9 is made to project below the bracket 7, and is attached at

that point to a lever, 11, which lever, by means of a connecting-rod, 12, is pivotally united with a horizontal plate, 13, secured to the sliding drop-bar 4 to the left of the center, the said drop-bar being adapted to receive a reciprocating motion through the medium of the rod 9. At equal distances each side the bracket 7 one end of a segmental bar, 14, is secured to the upper face of the transverse bar 6, which segmental bar is adapted to extend to the rear 55 of the machine, and is provided with horizontal parallel end portions, 15, as shown in Fig. 1.

An arm, 16, is pivotally attached to the bracket beneath the flange of the tube 8 by 60 means of straps 17, secured within the slotted inner end of said arm, the said straps being adapted to turn loosely upon the bracket.

The arm 16 is adapted to extend normally longitudinally the planter and project a distance beyond one box, 3, and is provided at 65 its outer end with a fixed bar, 18, at right angles to the arm, projecting outward an equal distance upon each side.

The outer ends of the fixed bar 18 are slotted, 70 and within said slots a grooved pulley, 19, is pivoted, and above said pulley a U-shaped guard, 20, is provided, attached to the slotted ends of the bar 18 by the same pivotal bolt carrying the pulleys. 80

Near the outer ends of the arm 16, upon the under surface, a spring-plate, 21, is made to project upon each side, which plate, engaging the under side of an upwardly-extending angular stop, 22, attached to the outer and forward side of the seed-boxes, as illustrated in 85 Figs. 1 and 2, serves to limit the outward throw of the said pivoted arm.

In the upper edge of the inner arm of the angle-irons a slot is cut, adapted to receive 90 the weighted end of a latch, 23, pivoted beneath the arm 16, the said latch being disengaged by the driver through the medium of a rope or cord, 24, attached to the inner end of the latch, as shown in Fig. 2.

Upon the upper outer end of the arm 16 a lever, 25, is pivoted, having a notched inner end and a metal loop, 26, formed upon the outer end, projecting across and beyond the fixed bar 18. A spring, 27, also attached to 100 the upper surface of the arm 16, is made to engage the notched end of the lever 25, adapted

to retain the same normally parallel with the arm.

About centrally the upper surface of the lever 25 a connecting-bar, 28, is pivoted, which bar, extending inward, is made to slide in ways 29, formed upon the arm 16, and a second short connecting-bar, 30, having a downwardly-bent inner end, is pivoted at its outer end to the long connecting-bar 28, to operate in unison therewith. The bent inner end of the short bar 30 is adapted to enter the elongated slot in the head 10 of the rod 9.

At each side of the ways 29, upon the arm 16, the right-angular arms of a U-shaped supporting-rod, 31, are pivotally secured, the inner closed end of which rod 31 is provided with two or more depressions to receive the short connecting-bar 30 and lift the same from engagement with the rod 9 when the bent inner end of the supporting-rod is brought in contact with the bar 14 as shown in Fig. 4.

In the operation of the planter a rope, 32, is stretched from one of a field to the other, provided at intervals with a series of balls, 33, the said rope and balls being adapted to pass through the loop 26 of the lever 25 and over the pulleys upon the fixed arm. As the planter is driven along, the balls, engaging the reduced ends of the loop 26, carry the lever 25 outward, as shown in Fig. 5, thereby causing the connecting rods 28 and 30 to slide forward, which, acting upon the rod 9 to turn the same, causes the drop-bar 4 to reciprocate in one direction, the said bar being almost immediately reciprocated in an opposite direction by the return of the aforesaid operating parts to their normal position. This opposite movement is produced by the balls 33, passing through the large end of the loop 26, whereupon the lever 25 is returned to its normal position by the spring 27. When it is desired to reverse the planter and sow another row, the cord 24 is pulled and the latch 23 lifted. The planter is then turned, which movement causes the arm to travel in the direction of the opposite seed-box. The supporting-bar 31 then coming in contact with the guide-bar 14, raises the short connecting-bar 30 out of engagement with the operative mechanism of the drop-bar. Thus the position of said bar is not changed when reversing. When, however, the arm 16 is locked over the opposite box, the connecting-bar 30 is made to re-engage the rod 9, and, the machine being driven forward, the planting is continued.

Having thus fully described my invention, I claim as new and desire to secure by Letters Patent—

1. The combination, with a planter, a slotted rod journaled between the boxes, the drop-bar reciprocating in said boxes, and a pivoted connection between said rod and drop-bar, of a swinging pivoted arm adapted to extend over and beyond the boxes, a spring-actuated lever pivoted upon said arm and having an elongated loop attached at the outer end, a pivotal dual rod-connection between said lever and slotted pin, a trip-bar pivoted to said arm beneath one connecting-bar engaging the aforesaid pin, a ball-carrying rope fast at each end adapted to be engaged by said loop, and means for operating the drop-bar from said pivoted arms when extended over the seed-boxes, substantially as shown and described.

2. The combination, with a planter, a slotted rod journaled between the boxes, the drop-bar reciprocating in said boxes, and a pivoted connection between said pin and drop-bar, of the swinging pivoted arm 16, the spring-actuated lever 25, pivoted on said arm, provided with an elongated loop, 26, the pivotally-connected and sliding connecting-bars 28 and 30, the fixed bar 18, attached at right angles to said arm, pulleys 19, pivoted in slots on said bar, and a ball-carrying rope passing through said pulleys and loop, substantially as shown and described.

3. The combination, with a planter, a slotted rod journaled between the boxes, the drop-bar reciprocating in said boxes, a pivoted connection between said drop-bar and rod, and a rearwardly-extending U-shaped guide-bar, 14, attached at each side of said pin, of the swinging pivoted arm 16, the spring-actuated lever 25, provided with an elongated loop, 26, the pivotally-connected and sliding connecting-bars 28 and 30, a right-angular bar, 31, pivoted to said arm beneath the connecting-bar 30, adapted to engage said guide, the fixed bar 18, carrying pulleys 19, and a ball-carrying rope, 32, passing over said pulleys and through said loop, and means for releasing and swinging said arm to the rear, substantially as herein set forth.
